UNITED STATES PATENT OFFICE.

FERDINAND P. HUEENER, OF CAMERON, TEXAS.

HYDRAULIC COTTON PRESS.

Application filed December 31, 1920. Serial No. 434,263.

To all whom it may concern:

Be it known that I, FERDINAND P. HUEENER, a citizen of the United States, residing at Cameron, in the county of Milam and 5 State of Texas, have invented certain new and useful Improvements in Hydraulic Cotton Presses, of which the following is a specification.

The main purpose and object of the invention 10 is to provide a power press particularly adapted, by construction and design, for use in the smaller gins whereby the cotton may be compressed, as it is ginned, to a density ready for the market; thereby eliminating the necessity for a re-pressing of the 15 bale.

An additional object is to provide a hydraulic press of the character above specified having certain constructional features 20 enabling it to be operated without the expenditure of very much power and of such strength as to compress the cotton, at any cotton gin having sufficient power to operate the press, and to complete the bale in as 25 short a time as possible with the ordinary press now in common use.

A further object is to provide a press having means for compressing the cotton into a bale, which when completed and out of the 30 press is almost round in shape, and thus, easier to handle than the customary square compressed bale.

With the above and other objects in view, which will become apparent as the description 35 proceeds, the invention may be said to reside generally in the details of construction, combination and arrangement of parts as will be hereinafter more fully pointed out and described, reference being had to the 40 accompanying drawings, wherein:

Figure 1 is a side elevation of the invention, the lower part being in section to illustrate the method of operation;

Figure 2, a horizontal sectional view, 45 taken on line 2-2 of Figure 1;

Figure 3, a similar section taken on line 3-3 of Figure 1;

Figure 4, a detail sectional view, disclosing 50 the manner in which the movable compressor enters the cotton container;

Figure 5, a sectional view of a part of the press which illustrates the shape of the upper and lower blocks or dies;

Figure 6, is a face view of the upper die,

Figure 7, a face view of the lower die, and 55 Figure 8, a transverse, vertical section of a die, disclosing the manner in which the parts are relatively connected.

The frame of the device comprises a plurality of uprights or rods which have their lower ends inserted through a bottom timber or sill 9, which, in turn, is supported upon elements 10, resting in a recess below the ground-line G-L as shown in Figure 1 of the drawings. These uprights are preferably three in number and include a stout rod 11 located at one end of the sill and a pair of laterally spaced rods 12, of slightly smaller diameter than rod 11, located at the other end, as may be seen in Figure 6. 60 These rods must be of such strength as to easily withstand the strain of the compressing operation. At their outer ends, the rods are connected by a stationary platen or head block 13 which, together with the compressor 65 elements carried thereby, constitutes the upper die. The ends of the rods extend through and beyond both the sill 9 and the block 13 and are threaded to receive adjustment nuts 14; cooperating nuts 15 being 70 provided inwardly of the blocks and sill to serve as locking elements for holding the parts in adjusted relation. By means of the lower set of adjustment elements, it is possible to adjust the uprights to various 75 heights limited only by the depth of the spaces provided at 16, below the sill. The upper set of adjustment nuts permit the head-block to be vertically adjusted relative 80 to the supporting uprights. 85

Depending through a central opening in the sill and between the uprights, is a hollow cylinder 17, having a flanged head 18 engaging the top of the sill and supporting the cylinder therefrom. Suitable fastening 90 means 19 are employed for connecting the cylinder to the sill. Mounted in the cylinder is an elongated, hollow plunger 20, having a snug fit therewith and slidable longitudinally therein under suitable pressure introduced into the cylinder through inlet 21. Packing rings 22 encircle the plunger, at its lower end, and provide for a snug fit with the bore of the cylinder. At its upper 100 end, the plunger is provided with a flanged head 23 upon which is secured the lower platen or block 24. The plunger is centered 105 with respect to the frame of the press so

that upper and lower die plates 13 and 24 are in line with each other and properly co-operate during the operation of the press.

Each platen is provided with a plurality of laterally spaced elements 25 disposed crosswise thereof and separately fastened in place, as indicated at 26. A corresponding number of such elements is provided on each platen and aligned in pairs to provide co-operating compressing surfaces between which the cotton of the container is compressed. Each element or compressor 25 is, moreover, provided with a concaved compressing face which, when coacting with the correspondingly shaped face of its companion member, tends to give the bale a round or elliptical shape, thereby enabling it to be more easily handled. Since each compressor 25 is separately fastened to a platen, it is obvious that it may be separately removed therefrom and hence the number of compressors carried by the platen may be varied from time to time, either increased or decreased at the will of the operator.

Arranged for movement between the upper compressor 13 and the lower or movable compressor 24, is the containing means for the cotton to be compressed.

This container comprises boxes or receptacles 27 into which the cotton is to be deposited, and these boxes may be of the usual and ordinary construction common to devices of like character, and being, in addition, considerably strengthened at the upper part by encompassing bands or braces 28. As the greatest pressure is exerted on the cotton when confined within the upper part of the box or cotton container, these braces serve to reinforce the box at the most necessary point and enable it to successfully withstand the pressure of the compressor. The boxes are tubular, being opened at each end and relatively connected by side-bars 29-29', embracing the boxes on opposite sides and adjacent the bottom and intermediate portions, as shown to advantage in Figure 1. The uppermost bars are relatively connected, inwardly of the cotton boxes, by means of a transverse strip 30, having a central opening through which rod 11 passes, collars 31 being fixed to the rod above and below the strip to provide a bearing therefor. A similar connection is provided for the lower set of side bars. Rod 11, therefore, provides an axis about which the cotton container revolves in a circular path, as indicated in Figure 3 of the drawings; it being noted that each block passes between uprights 11 and 12 once in every revolution. When the container is in the position indicated in Figure 3, one of the boxes, it will be noted, is positioned with its open end in direct line with the upper and lower compressors, and since the lower

compressor 24 is slightly less in size than the cross area of the aligning box, it is obvious that the latter is freely movable through the box, as indicated in Figure 4.

Mounted upon the top face of the upper block 13 is a group of supporting elements 32, rigidly connected to the block and providing a support for one end of a long beam or arm 33, which projects laterally beyond one end of the press frame, to provide means upon which any suitable packer mechanism may be mounted. A brace 34 provided upon one end of the block 13 and connected to the overhanging beam provides an auxiliary support for the latter and strengthens it. This beam extends over the revoluble cotton container, and enables the packer mechanism, which is not shown, to be properly mounted and positioned for packing the cotton in the box of the container which is disposed exteriorly of the frame, while the cotton in the other box is being compressed.

In the practical operation and adoption of the invention, the frame is to be preferably located in proximity to a cotton gin, so as to compress the cotton as it is ginned, the compression being to such a density as to condition the cotton ready for the market without requiring the bale to be re-pressed. As the cotton is ginned it is packed by any suitable means, into one of the boxes of the cotton container which is overhung by the packer mounting 33; any suitable packing mechanism being employed for packing the cotton in the container, prior to swinging the same into position between the compressors 13 and 24, between which it is ultimately compressed to the required density. The actuation of the plunger may be accomplished through hydraulic pressure, steam, or otherwise, the fluid being forced into the cylinder through opening 21 and acting upon the plunger which is raised thereby so that platen 24 is moved in the direction of platen 13, the cotton between being thus compressed into the shape defined by the concaved surfaces of elements 25. It will be seen that the concave surfaces of the elements 25 exercise a peculiar function in that they start the compression at the edges of the bale so that the material of such bale is crowded in toward the center as the bale is formed. Consequently the bale formed differs not only in shape but also in the internal structure and density arrangement of the bale, being compressed in such manner that no rebaling is necessary. Much of the pressure of the operation is borne by elements 25 themselves, which practically encircle the bale and thus relieve the side walls of the cotton container. The shape of the bale, when completed, and out of the press, is almost round or elliptical, and is therefore, adapted to be more conveniently handled than the square shaped

bale. The press is designed to be also used and operated by any large ginner, and will prevent to some degree, the accumulation of so much cotton at compresses, which so frequently proves a burden.

The foregoing description and accompanying drawings have reference to what might be considered to be the approved or preferred form of my invention. I desire it 10 to be understood that I may make such changes in the construction, combination and arrangement of parts, materials, dimensions, et cetera, as may prove expedient and fall within the scope of the 15 appended claim.

Having thus described my invention, what I claim as new and desire to secure by Letters Patent is:—

In a hydraulic cotton press, a base sill, 20 a depending centrally disposed cylinder carried by the sill, an upstanding post carried by the base sill at one side of the

plunger and arranged at the longitudinal axis of the sill, a pair of spaced upstanding guide rods arranged on the other side of 25 the plunger and carried by the sill, a head block secured to the post and guide rods, a slide block arranged between the guide rods, post, head block and sill, a depending centrally disposed plunger secured to the 30 head block and reciprocably mounted in the cylinder, concaved presser elements secured to the slide block and head block and arranged in spaced relation thereon, and a rotatable cotton container mounted 35 upon the post for movement between the sill and head blocks for reciprocably receiving the slide block.

In testimony whereof I affix my signature in presence of two witnesses.

FERDINAND P. HUEBNER.
